V. Z. CARACRISTI.
VALVE CUT-OFF AND SPEED INDICATOR.
APPLICATION FILED MAR. 8, 1922.

UNITED STATES PATENT OFFICE.

VIRGINIUS Z. CARACRISTI, OF BRONXVILLE, NEW YORK.

VALVE CUT-OFF AND SPEED INDICATOR.

1,419,612.

Specification of Letters Patent. Patented June 13, 1922.

Application filed March 8, 1922. Serial No. 541,941.

To all whom it may concern:

Be it known that I, VIRGINIUS Z. CARACRISTI, a citizen of the United States, and a resident of Bronxville, in the county of 5 Westchester and State of New York, have invented certain new and useful Improvements in Valve Cut-Off and Speed Indicators, of which the following is a specification.

10 This invention relates to valve cut-off and speed indicators for locomotives of that character wherein means is operatively correlated with the speed indicator for the purpose of correcting the position of the 15 cut-off valve in accordance with the piston stroke and speed of the engine in order to thereby maintain a predetermined ratio between the piston speed and the point of cut-off. A valve cut-off correction device 20 of this general character is fully described and broadly claimed in Patent No. 1,398,256 granted to me on November 29, 1921.

It is the primary object and purpose of my present improvement to provide means 25 whereby the operation of the valve cut-off indicator is automatically compensated to differences in the angular movement of the cut-off valve with respect to that of the operating gear.

30 It is a more particular object of my present invention to provide a corrective or compensating means controlling the operation of the valve cut-off indicator which is positive and reliable in its operation, as well 35 as being simple in its construction.

With the above and other objects in view, the invention consists in the improved actuating means for the valve cut-off indicator and in the form, proportion and relative arrangement of the several parts as 40 will be hereinafter more fully described, illustrated in the accompanying drawing and subsequently incorporated in the subjoined claims.

45 In the drawing wherein I have disclosed one simple and practical embodiment of the present invention and in which similar reference characters designate corresponding parts throughout the several views,

50 Figure 1 is a fragmentary side elevation in dotted outline of a locomotive, the valve cut-off indicator and its operating means being shown in full lines, and

55 Fig. 2 is an enlarged vertical section through the housing or casing for the com-

pensating or corrective means for the indicator.

Since reference may be readily had to my prior patent above identified, it will not be necessary to herein refer to the specific form and arrangement of the speed and valve cut-off indicating means which is mounted in the cab of the locomotive.

As disclosed in said patent, as the speed of the engine increases and the reverse lever 60 is actuated to correspondingly position the cut-off valve, such position will be indicated on the valve cut-off scale by movement of a hand or pointer which should at all times be positioned in corresponding relation to 65 the hand or pointer moving over a correlated speed indicating scale. For the purposes of the present explanation it will suffice to state that this indicating mechanism, generally designated in the accompanying drawing by the numeral 5, is conveniently mounted in the left hand side of the locomotive cab where it may be readily observed by the engineer. The movable hand or pointer of the speed indicating 70 scale is geared in any conventional way to one of the drive axles of the locomotive. The hand or pointer of the valve cut-off indicator is actuated through the medium of a vertically movable rod 6 which extends 75 downwardly through the floor of the cab and into a housing or casing 7 which is suitably mounted beneath the cab floor. The reverse lever 8 of the locomotive is operatively connected by means of the rod 80 9 and a bell-crank lever 10 to the valve operating gear 11. The bell-crank lever is fixed to one end of a tumbling shaft 12.

Upon the other end of the tumbling shaft 12, an arm 13 is fixed, said arm being pivotally connected to one end of a rod 14, the other end of which is connected to an arm 15 fixed upon one end of a shaft 16 which is journaled in the opposite side walls of the 85 casing or housing 7.

Within the housing 7 the lower end of the indicator operating rod 6 is connected to a horizontal arm 17 formed on the upper end of a bifurcated member 18. The spaced arms of the member 18 extend downwardly 90 and are slotted as at 19 to straddle the shaft 16. The member 18 is further provided with an upwardly projecting stem 20 which is movably guided in a sleeve 21 fixed to the top wall of the housing or casing 7. 110

A coil spring 22 surrounds the stem 20 and the sleeve 21 and bears against the member 18 to normally urge the same downwardly upon the shaft 16.

5 At one side of the bifurcated member 18 a gear 23 is fixed upon the shaft 16 and meshes with a pinion 24 secured on the shaft 25 which is likewise journaled in the side walls of the casing 7 in parallel relation to 10 the shaft 16. Upon this shaft 25 a cam member 26 is securely fixed and is disposed between the slotted arms of the member 18. A roller 27 is journaled between the spaced arms of the member 18 and is yieldingly 15 held in bearing contact with the edge of the cam 26 by the action of the spring 22. The gear 23 and pinion 24 may be of any desired ratio as will be determined by the form of the cam and the differences in angular movement of the valve gear and the cut-off valve.

As shown in Fig. 2 of the drawings, the cam 26 is in a neutral position. When the cut-off valve is actuated by a forward movement of the reverse lever 8 and the engine gathers speed, the valve cut-off indicator is likewise actuated by the movement of the rod 14 connected to the tumbling shaft 12, such movement transmitting a rocking or 30 oscillating movement to the shaft 16 and through the gear 23 and pinion 24 moving the cam 26 so that its higher edge portion 28 will ride upon the roller 27 and thus force the member 18 upwardly against the 35 action of the spring 22, moving the operating rod 6 for the indicator to a corresponding extent. In a reverse movement of the lever 8 to move the cut-off valve so that the locomotive is driven backwardly the edge 40 portion 29 of the cam 26 will coat with the roller 27, and it will be noted that this portion of the edge of the cam is concentric with the axis of the shaft 25 so that no movement will be imparted to the operating 45 rod 6 for the indicator. The cam 26 is provided with a slot 30 concentric with the shaft 25 to accommodate the shaft 16. In the drawing the cam 26 is illustrated in its full forward position in dotted lines at 50 A and in its full reverse position at B.

It will, of course, be understood that as the cam is returned from its full forward position by the operation of the reverse lever to a neutral position, the spring 22 constantly acts to maintain bearing engagement of the roller 27 on the edge of the cam so that the valve cut-off indicator will be accurately operated to precisely indicate the exact degree of cut-off which is necessary in order to maintain a predetermined driving speed with maximum operating efficiency. It will also be understood that a series of interchangeable cams 26 of different form or curvature may be provided and the proper 65 cam selected for the operation of the indi-

cator in accordance with the predetermined differences in the angular movement of the valve gear and the cut-off valve.

From the foregoing description it will be seen that I have devised a very simple and 70 compact arrangement of the corrective or compensating mechanism whereby the operation of the valve cut-off indicator may be accurately controlled regardless of the difference in the angular movements of the cut-off valve and the valve gear. It will also be readily seen that my present improvement can be easily adapted for use in conjunction with the valve cut-off and speed indicator disclosed in my issued patent. The device 75 as herein disclosed has been found very positive and reliable for the purpose in view and constitutes a very important addition to my original invention without complicating the latter or greatly adding to its production 80 cost.

While I have herein illustrated and described one practical and satisfactory embodiment of my present improvement, it will be apparent to those skilled in the art 90 that the same results may be obtained by the use of other alternative devices. Accordingly, I reserve the privilege of incorporating all such legitimate modifications in the form, proportion and relative arrangement of the several parts as may be fairly embodied within the spirit and scope 95 of the appended claims.

I claim:

1. In combination with the operating gear 100 for the cut-off valve of a locomotive and means for indicating the various positions of said cut-off valve; means for compensating the operation of the indicator to differences in the angular movement of the 105 cut-off valve with respect to the operating gear.

2. In combination with the operating gear for the cut-off valve of a locomotive and a reverse lever operatively connected to said 110 gear and means for indicating the various positions of the cut-off valve; means for actuating said indicating means in the operation of the reverse lever including means for compensating the operation of the indicator to differences in the angular movement 115 of the cut-off valve with respect to the operating gear.

3. In combination with the operating gear for the cut-off valve of a locomotive and a 120 reverse lever operatively connected to said gear and means for indicating various positions of the cut-off valve; means for actuating said indicating means when the reverse lever is moved in one direction and compensating the operation of said indicator by differences in the angular movement of the 125 cut-off valve with respect to the operating gear, said means being non-effective to actuate the indicating means upon a movement 130

of the reverse lever in an opposite direction.

4. In combination with the operating gear for the cut-off valve of a locomotive and means for indicating various positions of said cut-off valve; means for actuating said indicating means including a cam constructed to impart an operating movement to said indicating means in accordance with the differences in angular movement of the cut-off valve with respect to the operating gear.

5. In combination with the operating gear for the cut-off valve of a locomotive, a reverse lever operatively connected to said gear and means for indicating various positions of the cut-off valve; actuating means

for said indicating means including a cam operatively connected to the reverse lever, and a member connected to a part of the indicating means and yieldingly held in coacting engagement with the cam to be actuated thereby in a movement of the reverse lever in one direction and thereby impart an operating movement to the indicating means to an extent predetermined in accordance with the differences in the angular movement of the cut-off valve with respect to the operating gear.

In testimony that I claim the foregoing as my invention, I have signed my name hereunder.

VIRGINIUS Z. CARACRISTI.
